The ornamental design for a refrigerated display counter, as shown and described.

DESCRIPTION

FIG. 1 is a front perspective view of a refrigerated display counter showing my new design;

FIG. 2 is a front view of the refrigerated display counter of FIG. 1;

FIG. 3 is a rear view of the refrigerated display counter of FIG. 1;

FIG. 4 is a left side view of the refrigerated display counter of FIG. 1;

FIG. 5 is a top view of the refrigerated display counter of FIG. 1; and,

FIG. 6 is a rear perspective view of the refrigerated display counter of FIG. 1.

Bottom views are omitted since the bottom views are invisible in normal use.

Right side views are omitted since the right side views are mirror images of the left side views.

In the drawings, the broken lines depict portions of the refrigerated display counter that form no part of the claimed design.
